B. ZOLL & J. DOYLE.
MAKING SOAP.

Patented July 19, 1830.

Domestic and Foreign People of Baltimore, Md.

The following formula has been tried and making part of the same containing a description in the words of the said Edward Gill and James Doyle themselves of their improvement in the art of making Soap by the application of Lime.

To all to whom these presents shall come. Be it known that Mr. Bernard
Joll and James Doyle of the City of Baltimore and State of Maryland have invented
a new and useful improvement in the art of making soap by the application
of steam to that purpose, and that the following is a full and exact description
of the construction and operation of said improvement as recorded by us.

On the annual drawing (F.) represents the flue D the fire door with the ash hole under it, and (B.) the chimney. (B.) is the Steam Boiler with a safety valve at (a), two stop cocks at b.b. for regulating the water line therein, a plate (E) covered by sand and strong iron crofs bars, b.b. so as to admit of its being removed, for the purpose of cleaning out the boiler and on iron steam pipe P. which conveys the steam from the boiler to the wooden conducting pipes Q.R. which latter may also be of copper or iron, but we find well banded wood pipe to answer the purpose equally well if not better, for they are sufficiently strong to resist the pressure of the steam and more better to keep the heat. O is a reservoir (which may be a large lead or pipe) elevated upon a frame above the boiler and supplied from the pump (S) it communicates with the boiler by the tube (n) which has a stop cock at (f) for admitting water into the Boiler. F.F. are large conical, busters which may also be of iron or copper, but we prefer wood the number of which may be multiplied as occasion requires also their height may be regulated so as to suit the Building in which they are placed, each of them has a large stop cock at (I), and is covered with a cover lid which is one piece, and supplied with hinges (d.h.) so as to admit the holes (x.x) to be opened. (W.W.) are wooden tubes connected by means of lateral tubes and stop cocks, 2.2. with the conduct - P. and descending through the lids or coverings of the vessels F.F. to the bottom, on which they rest, are longitudinal and perforated within, - such as to have more evaporation as soon dotted in the drawing, they have a collar or flange immediately above the perforations.

X 6074

for the purpose of purifying the soap and extracting the impurities from the Boilers and at the upper extremity of the tube (g) there is a plug of spigots n.r. It is a stopper of platinum for the purpose of taking the soap out so as to enable them to stir the contents of the boiler H.H. The raw materials furnishing the soap being prepared in the common way once in paste are put into the Boilers H.H. after which the steam boiler B is filled with water from the reservoir and pump. The steam rising from the boiler fills the conductor tube R which being closed at both ends. on the stop cock s.2. being opened the steam enters & descends the tube S.S. and the steam pressure being increased of necessity it will continue to descend displacing the soap & till it escape through the perforations at the foot of the tubes. this operation and stirring occasionally is continued till the soap in the boiler H.H. is finished and fit to be dipped off. it is then formed in the usual way. the waste soap being discharged from the boilers through the cocks T.T. The spigots n.r. are mostly found accident in very cold weather. for it sometimes happens that the soap or soap congeals in the tube S.S. during the night. a particular attention must be paid to taking out the spigots n.r. .... removing the obstruction before the steam is admitted. The advantage of our method over the old way of boiling soap are. 1st. that it requires much less stirring and although the temperature of the liquor is kept up much higher than in the old way. the soap is not at all subject to being burnt which frequently happens during the process in the old way. it makes the soap brighter and saves a large percentage of fat. there is also no risk of breaking kettles which is a very common accident in the old way of boiling. In addition to the soap boilers H.H. we also have connected with the conductor R a lattice-mitter (C) which is a wooden iron, copper, or lead covered close and enclosing a wimble dotted in the pine) which connects with the conductor R by the tube (g); the steam passing through the wimble keeps the lattice in the mitter in a proper state for dipping or moulding candle, and the temperature can be increased or abated at will by shutting off or opening up of the steam by the by the stop cock (h) the mitter also has a stop cock (j.) for taking off the tallow as it is wanted. also the top is contrived to be taken off in the form of a tiered ² fallow. Now what we claim as our invention or improvement is, the application of steam to boiling soap and the use of a lattice-mitter

Received from Mr. Joseph for the purpose of being made available and
delivered on the day of July 1930.
